(57) **CLAIM**

The ornamental design for an awning, as shown and described.

DESCRIPTION

FIG. 1 is a top perspective view of an awning, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof;

FIG. 10 is an enlarged detail view of area 10 in FIG. 1 thereof;

FIG. 11 is an enlarged detail view of area 11 in FIG. 2 thereof;

FIG. 12 is an enlarged detail view of area 12 in FIG. 2 thereof;

FIG. 13 is an enlarged detail view of area 13 in FIG. 2 thereof;

FIG. 14 is an enlarged detail view of area 14 in FIG. 2 thereof; and,

FIG. 15 is an enlarged detail view of area 15 in FIG. 8. The dash-dot-dash broken lines encircling the enlarged views are for annotative purposes only and form no part of the claim thereof.

1 Claim, 15 Drawing Sheets
